CLAIM

The ornamental design for a wall-integrated transaction device form, as shown and described.

DESCRIPTION

FIG. 1 is a perspective view of a wall-integrated transaction device form of a ninth example embodiment of our new design.

FIG. 2 is a front view of the wall-integrated transaction device form of the ninth example embodiment.

FIG. 3 is a back view of the wall-integrated transaction device form of the ninth example embodiment.

FIG. 4 is a left side view of the wall-integrated transaction device form of the ninth example embodiment.

FIG. 5 is a right side view of the wall-integrated transaction device form of the ninth example embodiment.

FIG. 6 is a top view of the wall-integrated transaction device form of the ninth example embodiment; and,

FIG. 7 is a bottom view of the wall-integrated transaction device form of the ninth example embodiment.

The broken lines shown in the drawings are for illustrative purposes only and form no part of the claimed design. The shade lines in the figures show contour and not surface ornamentation.
